J. H. PRIMM.

IRONING BOARD.

APPLICATION FILED AUG. 21, 1916.

1,213,255.

Patented Jan. 23, 1917.

FIG. 1

UNITED STATES PATENT OFFICE.

JAMES H. PRIMM, OF CHICAGO, ILLINOIS.

IRONING-BOARD.

1,213,255.

Specification of Letters Patent. Patented Jan. 23, 1917.

Application filed August 21, 1916. Serial No. 115,984.

To all whom it may concern:

through the ears and leg to fasten the plate.

I claim as my invention:
In a device of the class described, a board
and a supporting leg pivotally mounted in
said board, said device being adapted to be
5 attached to a table with the table edge
clamped between the opposed ends of the
board and leg, said leg being notched, a

brace, one end of which is pivoted to said
board and the other end of which seats in
said notches, and a spring connecting said 10
brace and said leg.

In testimony whereof, I affix my signature.

JAMES H. PRIMM.
